By his Attorney, *J. R. Littell*,
Inventor, *Irving W. Stearns*,

UNITED STATES PATENT OFFICE.

IRVING W. STEARNS, OF CENTER BARNSTEAD, NEW HAMPSHIRE.

NAIL-PULLER.

SPECIFICATION forming part of Letters Patent No. 700,846, dated May 27, 1902.

Application filed July 27, 1901. Serial No. 70,194. (No model.)

To all whom it may concern:

Be it known that I, IRVING W. STEARNS, a citizen of the United States, residing at Center Barnstead, in the county of Belknap and State 5 of New Hampshire, have invented certain new and useful Improvements in Nail-Pullers, of which the following is a specification.

This invention relates to nail-pullers; and it has for its object to provide an improved 10 device of this class which may be readily and conveniently operated by a claw-hammer or similar device and shall constitute in itself a simple, inexpensive, and relatively small device adapted to be conveniently carried in the 15 pocket or otherwise.

In the drawings, Figure 1 is a side elevation of my improved nail-puller, showing the same in use. Fig. 2 is a detail transverse sectional view taken upon the line $x-x$, Fig. 1. Fig. 3 20 is a plan view of the improved nail-puller.

Corresponding parts in all the figures are denoted by the same reference characters.

Referring to the drawings, 1 designates my improved nail-puller, which comprises a body member 2, embodying a fixed jaw 3 and a relatively movable jaw 4. The body member 2 also embodies a foot 5, whereby by means of the fixed jaw 3 and said foot 5 the body member 2 may be rested upon the work 6, with the 30 jaws 3 and 4 in position to be engaged with the nail 7. The movable jaw 4 projects above the body member 2, as at 8, and is formed to receive the claw 9 of an ordinary hammer, as illustrated at 10, whereby the 35 head 11 of the hammer may be rested upon the top surface of the body member 2, and, with the claw 9 in operative engagement with the upwardly-projecting portion 8 of the jaw 4, said hammer may be swung upon the body member 2 as a fulcrum in the same mode of 40 operation as would be employed were the claw 9 directly engaged with the nail to be extracted. This operation, with the jaws 3 and 4 in gripping engagement with the nail, pivotally 45 moves the jaws 3 and 4 relative to the work 6 upon the foot 5 as a pivotal support and causes the extraction of the nail from the work. In the preferred form of construction the body member 2 is of integral construction 50 and may be cast, forged, or otherwise formed to embody a central shank 2^a and two inwardly-curved end portions 12 and 13, re-

spectively, which end portions are respectively formed into the fixed jaw 3 and the foot 5. The metal of which the body member 2 is composed is thickened at a point adjacent the fixed jaw 3, as at 14, and is vertically chambered, as at 15, to receive the movable jaw 4, which consists of a single piece of suitable metal 16, which is curved at one end, as at 17, to form the jaw proper, and the other end of which is of sufficient size to project above the body member 2 and is provided upon its opposite side faces with shoulders 18, beneath which the bifurcations of the claw 9 of the hammer may be fitted. The metallic piece 16, which embodies the jaw 4, is pivoted, as at 20, between the cheeks 19, formed by chambering the body member 2, which chamber 15 is of proper dimensions to permit of pivotal movement of the metallic piece 16 longitudinally of the body member to a considerable extent. The jaws 3 and 4 are oppositely curved, as illustrated, and are provided, respectively, with pointed operative end portions 21 and 22, whereby they may be operatively forced into the work surrounding the nail, and thus engaged with the head of the latter. The bases of the pointed end portions 21 and 22 of the two jaws and the base of the curved foot 5 or one or more of the same are formed with sufficient width to support the device in upright position upon the work during the operation of driving the pointed jaws into the latter.

The operation and advantages of my improved nail-puller will be readily understood. The foot 5 and the jaws 3 and 4 are placed upon the work with the nail to be removed between the points 21 and 22 of the jaws. 90 The points of the jaws are then forced into the work until they are beneath the level of the head of the nail and in entering the work tend to approach the nail because of their oppositely and outwardly curved formation. 95 The claw 9 of the hammer is then caused to straddle the upwardly-projecting portion 8 of the movable jaw 4, the bifurcations of said jaw being fitted beneath the shoulders 18. In this position the top surface of the head 11 of the hammer rests upon the top surface of the body member 2 of the device, which body member 2 serves as a fulcrum or bearing for the hammer, which is swung upon the 100

same until the nail is started from its position, after which movement a continuation of the swinging movement of the hammer causes the top member 2 to rise pivotally, the jaws 3 and 4 swinging upon the curved foot 5, which latter serves as a pivotal bearing. This pivotal movement of the device is continued until the nail has been extracted from the work.

- 10 In the operation of forcing the pointed ends of the jaws 3 and 4 into the work the required result may be obtained by subjecting the body member 2 or upwardly-projecting portion 8 of the jaw 4 to the blows of a hammer or other suitable implement. The hammer, which in combination with the nail-puller performs the final extraction of the nail, may thus be used both for this purpose and for the purpose of initially forcing the pointed ends of 15 the jaws of the nail-puller into the work to grip the same in engagement with the nail. It is therefore in the use of a hammer only necessary to first employ the hammer-head to drive the jaws into the work and to then 20 engage the bifurcations of the claw of the hammer with the upwardly-projecting portion 8 of the jaw 4 and swing the hammer quickly to cause the pivotal elevation of the jaws 3 and 4 and the consequent extraction 25 of the nail.

The entire device is very simple and inexpensive, and in contradistinction to devices of this class as ordinarily constructed the device is of very small bulk and light in weight

30 and may be readily carried by the workman or other user of the same in the pocket. Being of few and simple parts, the device is possessed of considerable rigidity and is not likely to readily get out of order.

35 I do not desire to be understood as limiting myself to the details of construction and arrangement as herein described and illustrated, as it is manifest that variation and modification may be made in the features of 40 construction and arrangement in the adaptation of the device to various conditions of use without departing from the spirit and scope of my invention and improvements. I therefore reserve the right to all such variation 45 and modification as properly falls within the scope of my invention and the terms of the following claims.

Having thus described my invention, I claim and desire to secure by Letters Patent—

50 1. An improved nail-puller, comprising a body member adapted to rest upon the work and embodying a fixed jaw, and a movable

jaw carried by said body member in opposition to said fixed jaw and provided with a 50 projecting portion adapted to be engaged by a hammer or other implement whereby the latter may be operatively borne upon said body member to grip the jaws in engagement with the nail and to oscillate the entirety to 55 extract the nail.

2. An improved nail-puller, comprising a body member adapted to rest upon the work and embodying at one end a fixed jaw, and a pivoted jaw carried by said body member in 70 opposition to said fixed jaw and provided with a projecting portion which extends above the body member and is adapted to be engaged by a hammer or other implement whereby the latter may be operatively borne upon said 75 body member to grip the jaws in engagement with the nail and to oscillate the entirety to extract the nail.

3. The combination, with a nail-puller comprising a body member adapted to rest upon 80 the work and embodying a fixed jaw, and a movable jaw carried by said body member in opposition to said fixed jaw and provided with a projecting portion which extends above the body member; of a claw-hammer the bifurcations of the claw of which are caused to straddle said projecting portion of said movable jaw whereby the head of the hammer may be operatively borne upon said body member to grip the jaws in engagement with 85 the nail and to oscillate the entirety to extract the nail.

4. An improved nail-puller, comprising an elongated body member adapted to rest upon the work and embodying at its respective 95 ends a fixed jaw and a curved foot, said body member being chambered vertically adjacent to said fixed jaw to form cheeks, and a movable jaw pivoted between said cheeks and arranged in opposition to said fixed jaw, said 100 movable jaw being provided with a projecting portion which extends above the body member and is adapted to be engaged by a hammer or other implement whereby the latter may be operatively borne upon said body 105 member to grip the jaws in engagement with the nail and to oscillate the entirety to extract the nail.

In testimony whereof I have signed my name in the presence of the subscribing witnesses.

IRVING W. STEARNS.
